UNITED STATES PATENT OFFICE.

KUNISUKE SUYEHIRO, OF EUREKA, UTAH.

GAME.

1,321,405.

Specification of Letters Patent. Patented Nov. 11, 1919.

Application filed September 3, 1918. Serial No. 252,452.

To all whom it may concern:

Be it known that I, KUNISUKE SUYEHIRO, a subject of the Emperor of Japan, residing at Eureka, in the county of Juab and State 5 of Utah, have invented a new and useful Game, of which the following is a specification.

This invention has reference to games, and its object is to provide a form of game in 10 which a game board is employed and in which the plan of the game is similar to but in certain respects different from the game of checkers.

In accordance with the invention, the 15 game board, which may be of rectangular outline, is divided off into squares and diagonal lines with the intersections constituting stopping points. At one part of the board, preferably though not necessarily 20 the top of the board, is a circumscribed space having a single point of entrance, into which space it is the purpose of the game to drive a certain checker constituting the sole checker belonging to one side.

25 The nature of the game is such that the one checker may win the game from sixteen other checkers constituting the opposing side, or the one checker may be driven into the inclosed or circumscribed space from 30 which escape may be blocked.

The invention will be best understood from a consideration of the following detailed description taken in connection with the accompanying drawing forming part of 35 this specification, with the understanding, however, that the invention is not confined to any strict conformity with the showing of the drawing but may be changed and modified so long as such changes and modifications 40 mark no material departure from the salient features of the invention as expressed in the appended claim.

In the drawing:—

Figure 1 is a plan view of a game board 45 arranged in accordance with the invention.

Fig. 2 shows plan views of checkers used in the game.

Referring to the drawing, there is shown 50 a board 1 which may be quite similar, in general form, to the well known checker board. The board is provided with a playing face 2, shown in the drawing as of generally rectangular shape, divided by lines 3, 4, in perpendicular relation to each other, 55 into numerous squares and these squares are

each divided by diagonal lines 5 into right-angle triangles. At the intersections of the lines 3, 4 and 5 are indicia 6, shown in the drawing as circles, so as to indicate stopping places for the playing devices. To outline 60 the playing space is a border line 7 spaced away from the outer edges of the board to provide a border 8 which may be ornamented in any desired manner or may be free from ornamentation. 65

The playing space is made shorter than the length of the board, which latter may be longer in one way than in the other, and the playing space terminates closer to one end of the board than to the other. This leaves 70 room for a space 9 placed diagonally with relation to the squares in the playing space 2 and so related to the border line 7 that a station or stopping place 6 occurs at the entrance to the space 9, which latter contains cross lines 3 and 4, while the border line is arranged diagonally, as indicated at 7a. 75

The game board may be ornamented in any way desired but no particular description 80 of such ornamentation need be given.

In order to play the game, checkers or, as sometimes designated, "men," 10, 11 are provided, these checkers being seventeen 85 in number in the particular arrangement shown in the drawings, sixteen of the checkers being of one color and one of the checkers being of another color, or the checkers may be otherwise differentiated. For convenience it may be considered that the 90 checkers 10 are all red and the checker 11 is blue, the purpose being solely for distinction.

In order to play the game, the red checkers are placed upon all the marginal stations 95 6, there being sixteen such stations, and the blue checker is placed upon the central station 6. Each checker may be moved one space at a time, as in the ordinary game of checkers. 100

In playing the game either side may start. The plan of attack of the blue checker is to get between two red checkers, in which case the two red checkers become dead and are removed from the board. The plan of attack of the red checkers is to avoid such contingency but at the same time force the blue checker toward the isolated square 9 and ultimately to the end thereof, whereupon, the blue checker, being unable to es- 110

cape, loses the game. If the blue checker is enabled to reduce the number of red checkers to less than four, the game is won by the blue side. The playing of the game does not 5 contemplate jumping as in the ordinary game of checkers.

The devices used in playing the game are usually made round like checkers and may contain a representation 12 of any suitable 10 kind, the particular representation shown in the drawing being that of a knight, and the game being preferably known as Sixteen Knights. The game is intended particularly for children or youths and the name 15 and pictorial representations on the checkers and on the game board may be such as to appeal to younger people. These features, however, are susceptible to change and may be modified as the manufacturer 20 desires.

What is claimed is:—

A game comprising a game board having a playing face divided by crossed lines into squares, with each square divided by diagonal lines into an orderly continuous arrangement of right-angle triangles grouped 25

about a central point and with the intersections of the lines designated, and the playing face having outside of its limit a single rectangular extension arranged in diagonal 30 relation to the main part of the playing face and separated into right-angle triangles by lines crossing each other and terminating at the corners of the rectangular extension, said rectangular extension being connected 35 to the main playing face by a single contracted entrance gate at one corner, and a single playing device for one player and a plurality of playing devices for another 40 player, whereby the player provided with the plurality of playing devices may ultimately drive the other player with the single playing device into the far corner of the rectangular extension of the playing face. 45

In testimony, that I claim the foregoing as my own, I have hereto affixed my signature.

KUNISUKE SUYEHIRO.
